UNITED STATES PATENT OFFICE.

PAUL A. DRUCKLIEB, OF NEW YORK, N. Y., ASSIGNOR TO NEW YORK CIGARETTE MACHINE COMPANY, OF NEW YORK, N. Y., A CORPORATION OF NEW YORK.

MACHINE FOR FINISHING CIGARETTE-SEAMS.

1,152,716.

Specification of Letters Patent. Patented Sept. 7, 1915.

Application filed March 18, 1913. Serial No. 755,104.

To all whom it may concern:

Be it known that I, PAUL A. DRUCKLIEB, a citizen of the United States, and a resident of New York, county of New York, and State of New York, and whose post-office address is 14 Park Place, New York city, county of New York, and State of New York, pray that Letters Patent may be granted to me for Improvements in Machines for Finishing Cigarette-Seams, of which the following is a specification.

My present invention relates to certain novel constructions to be used for the purpose of finishing the seam in a pasted cigarette rod.

The particular type of device to which my present invention is directed embodies the idea of a presser finger or blade, preferably, having a contact surface where it bears upon the seam, of a little more than the width of the seam, so that the pressure exerted by the blade on the seam will be substantially co-extensive with its width, and additionally wherein the pressure of the blade gradually increases as the movement of the cigarette rod under the presser finger bar progresses. Such a type of seam finishing device is shown and described in the application for Letters Patent which I filed jointly with Daniel Hemming on the 31st day of May, 1912, Ser. No. 700,609. It is to a device of this class which my present invention relates, and it consists in novel structures or embodiments of the underlying ideas set forth in said application, which will be hereinafter more fully described, and finally set forth in the claims appended hereto.

In the drawing forming part of this application, Figure 1 is a perspective view of a portion of a cigarette making machine, and a like front view of my improved seaming device secured in operative position thereto. Fig. 2 is a like view taken at the rear of Fig. 1. Fig. 3 is an enlarged sectional elevation, the section being taken substantially on the line 3—3 of Fig. 1, looking in the direction of the arrows. Fig. 4 is an enlarged sectional elevation taken on the plane of the line 4—4 of Fig. 1, looking in the direction of the arrows. Fig. 5 is a perspective view of a modification. Fig. 6 is an end view of the same. Fig. 7 is a sectional elevation on the line 7—7 of Fig. 5, looking in the direction of the arrows. Fig. 8 is a longitudinal sectional elevation of a further modification,

the section being taken on the plane of the line 8—8 of Fig. 10. Fig. 9 is a side elevation of the same. Fig. 10 is a plan view. Fig. 11 is a transverse sectional elevation on the plane of the line 11—11 of Fig. 9, looking in the direction of the arrows; and Fig. 12 is a perspective view, showing a further modification.

Like reference characters indicate similar parts throughout the several views.

The embodiments of my invention, as shown herein, are adapted to a conventionally constructed cigarette making machine. They, however, may be adapted to machines specially designed, without much difficulty. So far as my present improvements are concerned, the only essential parts of the cigarette making machine that it is necessary to describe here is the conveyer tape which conveys the cigarette rod to the seaming and finishing device, a tube through which the tape passes after or during the time the lap of the seam has been formed and pasted, means for propelling the tape and cigarette rod, and suitable supports for the said devices. I shall describe only that much of the cigarette making machine which is embraced in the foregoing statement, as I deem that to be sufficient for the purpose of illustrating the application of my invention.

At 1 is a portion of the bed of a cigarette making machine. At 2 is a plate constituting the terminal portion of the grooves through which the conveyer or propelling tape and the cigarette rod move. A thumb screw 2^a may be used for detachably seaming the parts together. In devices of this kind, there is usually in advance of the terminal of the grooves, means for lapping and pasting the edges of the paper surrounding the tobacco core, and for guiding the pasted rod and tape through the terminal block and to the ironing or finishing means.

The cigarette rod, comprises the tobacco filler 3 and the paper covering 4 having the overlapped edges 5 and 6.

At 7 is the propelling wheel about which the conveyer tape 8 passes and which acts as the means for propelling the tape and cigarette rod through the machine. The edges of the tape, when embracing the cigarette rod do not meet, so that when the rod and encircling tape pass the pasting and finishing devices access to the seam of the rod may be had between their edges.

The foregoing are conventional parts, and may be constructed as shown, or modified to suit the particular requirements.

I shall first describe the embodiment of my invention as shown in Figs. 1 to 4 inclusive. At 9 is a plate provided with screw holes 10, by means of which it can be readily attached to the frame or bed-plate 1, (or any other appropriate portion) of the machine, in proper relative position to the plane of movement of the cigarette rod. The plate 9 has arms 10 and 11 in which are included upright sections 12, 13 so as to elevate the parts supported by the frame over and above the plane of the cigarette rod. The arm 11 is provided with an upright section 14 having a lug 15, and the arm 10 with an upright head 16. At 17 is a block recessed to bear against the rear and side of the section 14, and provided with a slot 18, through which projects a set screw 19, by means of which the block may be adjusted up and down relatively to the arm 14; and at 20 there is another set screw or stop, which is threaded through the lug 15 and which may be caused to bear against the top of the block 17 to limit the upward movement of the same and set it at the desired relative height. The head 16 is doubly bored as at 21, 22, the bore 21 being interiorly threaded and provided with a set screw 23 against the bottom of which bears a spiral spring 24, which latter passes down into the bore 22. The head 16 is also provided with a slot 25, which is formed in its bottom and which opens into the bore 22 and in line with both bores 21 and 22. At 26 is the finishing element of the device, comprising what I call a presser blade. By reference to Fig. 4 it will be seen that this blade has greater depth than width and that the operative or finishing surface or edge 27 is substantially co-extensive in width with the width of the seam, so that, as explained in my before-mentioned application, the pressure exerted by the blade upon the seam, and its bearing thereon, as shown in Fig. 4, will be approximately that of the lateral dimensions of the seam itself, leaving the balance of the rod undisturbed. That is, the ironing or finishing function of the blade is confined to substantially the lateral limits of the seam itself, instead of putting the entire rod under pressure. Of course, it is only essential, so far as this feature of my invention is concerned, that the contact or operative surface 27 of the blade has this characteristic, the rest of the blade being constructed as desired; my present invention relating only to means for supporting and operating it. The blade 26 is supported so that its heel 28 (Fig. 1) will lie in a higher plane than the toe portion 29, the heel being located adjacent the point of exit of the pasted rod from the guiding tube or channel 1^a, the in-

clination being indicated by the line α — α in Fig. 1. The block 17 is provided with a lateral and threaded bore 30 into which is let the threaded stem 31 of a set screw 32, which is provided with a collar 33 and a flange 34. The blade 26 is provided with an aperture through which the stem 31 is passed and in which the collar 33 is received, the collar 33 forming a bearing for pivotally supporting the blade thereon, and the flange 34, together with the projection 35 on the block 17 providing means for confining the blade in its proper relative position. The front or free end of the blade passes into the slot 25 formed in the head 16 and bears against the lower end of the spring 24, the sides 36 of the head forming a guide for supporting the blade in the proper relative upright position permitting it to move therein, and restraining it from lateral movement. By means of the screw 23, the pressure of the spring 24 on the blade can be regulated, which will also effect a change in the amount of inclination given it relative to the plane of the seam of the cigarette rod, cause the pressure of the contact to be a gradually increasing one, and at the same time afford means for placing upon the blade at the point where the force of its contact upon the seam of the cigarette rod is desired to be the greatest, a variable pressure, so that the contact of the blade with the seam at its front end will be elastic or yielding, as it will then readily yield to any irregularities in the same, and exert a gentle pressure thereon. This is very important when it is borne in mind that the desired action of the presser blade is to measurably pull or draw back the parts of the rod which constitute the seam, as by the action of the tip of the finger or the nail drawn along the surface of a piece of paper, at the same time distributing the paste or other adhesive material, by means of which the lap of the seam is secured together. By the means herein shown, the pivot of the blade is located adjacent the exit of the cigarette rod from the controlling tube or groove and may be adjusted up or down and retained in the desired adjusted position so as to secure the desired relative height, and that the means for regulating the amount of depression of the blade, for placing upon the seam of the cigarette-rod a yielding or elastic pressure, and for regulating this pressure, are located rearward of the pivotal support of the blade and at or adjacent its toe or point of greatest inclination, to the horizontal.

It will be noted that the device is very simple, avoids the use of heat artificially applied, and may be readily attached to any otherwise suitably constructed cigarette machine.

In Figs. 5 to 12 inclusive, I have shown modifications which embody to a greater or

lesser extent the principles of construction contained in the device shown in Figs. 1 to 4 inclusive. Referring first to Figs. 5, 6 and 7, at 37 is a plate adapted to be secured to the bed 1 of the machine by a screw 38. The plate has two arms 39, 40, the arm 39 being provided with a head 41 which is slotted at 42, into which slot passes the stem of a set screw 43 threaded into the head 41, and the arm 40 is provided with a head 44 slotted as at 45. Both heads are bored as at 46, in which bore lies a spring 47, and into which bore a set screw 48 is threaded, which bears on top of the spring. The presser blade 26 is not pivoted to either of the blocks but is loosely or freely set into their respective slots, as shown in Fig. 5, so that it will bear upon the seam of the cigarette rod by the action of the springs. Either or both of the screws 43, 48 may be adjusted to cause the springs 47 to bear with greater or lesser pressure on the blade and regulate both its height and inclination. The blade is provided with a lug 49 at the end where it engages with the head 41 and through this lug is passed a pin 50, which bears against the sides of the head 41. The function of this pin is to prevent the forward movement of the blade in the direction of the movement of the cigarette rod.

In Figs. 8 to 11 inclusive is shown a further modification. In these views the presser blade comprises a block 26^a, which in cross section is in the shape of a truncated pyramid, its operative or contact surface 27^a (shown diagrammatically in Fig. 11) being substantially of the lateral dimensions of the seam of the cigarette rod. The blade 26^a is removably and detachably secured to the plate 2 by providing the latter with a short recess 51 (Fig. 8) and the former with a lug or projection 52 which is let into the recess, this form of connection being had mainly for the purpose of preventing the blade from becoming laterally displaced, at the same time providing a movable connection of it with the supporting blade 2. At 53 is a flat bow spring having flattened ends 54, 55, the end 54 being screwed to the flat top 56 of the blade 26^a adjacent its toe portion 29, the end 55 being provided with a hole through which is passed the threaded stem 57 of the fastening screw 58, which has a flange 59 bearing on top of the end 55 of the spring, the plate 2 having a tapped hole receiving the threaded stem 57. By means of these devices the spring may be readily and detachably secured to the plate 2 or any other desired portion of the machine. The spring 53 causes the blade 26^a to bear down on the seam with a yielding pressure and gives to it the desired angle of inclination, as indicated by the dotted line α in Fig. 9. It will be noted that the heel 28 of the blade is capable of yielding and ex-

erting a relatively light pressure upon the seam of the rod as the latter emerges from the controlling or guiding tube, and that this pressure increases with the amount of pressure exerted by the spring 53, the latter giving the presser blade the desired amount of downward inclination at the toe portion 29.

In Fig. 12 is shown another modification, in which the presser blade 26^b is suspended over the plane of the cigarette rod by rods 60 fixed in the bed 1 which pass into guides 61 fixed to the blade, and which hold the blade in its proper position relative to the seam and prevent its lateral displacement, while permitting of its vertical movement. At 62 is a sectional weight resting upon a shoulder 63 on a rod 64, which is suitably secured to a lug 65 on the blade 26^b. The weight may be varied like the conventional weights on a scale. The operative or contact edge 27^b, in this form of the device, may be parallel with the plane of the seam, but I prefer, in order to realize all the benefits of my invention, that it be inclined at an angle, as shown by the dotted line α — α , so that the heel 28 will be higher than the toe 29 and exert upon the seam a gradually increasing and preferably yielding pressure in the direction of the length of the seam.

From the foregoing, it will be noted that my invention may be variously modified, without departing from its spirit.

I do not claim, in this application, the specific forms of the devices shown in Figs. 8 to 12 inclusive as they form the subject matter of further applications filed by me, said applications having been filed on the 3rd day of August, 1913, Serial Nos. 782,607 and 782,608.

I claim:—

1. In a machine for finishing cigarette seams, the combination with a suitable support, of a pressure blade pivotally secured at one end to said support, means for vertically adjusting said pivot and the height of the lower edge of the blade, and further means operating upon the free end of the blade for exerting thereon a yielding and adjustable pressure and giving the desired amount of downward deflection thereto.

2. In a machine for finishing cigarette seams, the combination of a frame comprising a plate, arms extending therefrom, a presser blade, means for pivotally securing the presser blade at one end to one of said arms, and a guide secured to the other of said arms for providing a movable engagement with the free end of said blade.

3. In a machine for finishing cigarette seams, the combination of a frame comprising a plate, arms extending therefrom, an upright extension from one of said arms, a block adjustably secured to said upright extension, a presser blade pivoted to said block,

- 5 a guide-head secured to the other arm mov-
ably engaging the free end of the blade, and
means for exerting a yielding and adjustable
pressure on the blade carried by said guide
head.
- 10 4. In a machine for finishing cigarette
seams, the combination with the presser
blade, a pivotal support for the same at one
end, a guide for its free end, a spring in said
guide bearing on said blade, and means for
adjusting the tension of the spring.
- 15 5. In a machine for finishing cigarette
seams, the combination with a frame, a block
vertically adjustable in said frame, a presser
blade pivoted to said block, a guide head
secured to said frame and movably engaging
said blade, a spring in said head engaging
said blade, and means for adjusting the ten-
sion of said spring.
- 20 6. In a machine for finishing cigarette
seams, the combination with a frame, a block
vertically adjustable in said frame, an adjust-
able stop secured to said frame coöper-
ating with said block, a presser blade piv-
oted to said block, a guide head secured to
said frame and movably engaging said blade,
a spring carried by said head pressing on
said blade, and means carried by said head
for adjusting the tension of said spring.
- 25 7. In a machine for finishing cigarette
seams, the combination with a frame or sup-
port, a block engaging said support and
vertically movable relative thereto, a slot in
said block, a set screw passing through said
block and engaging said support, an adjust-
able stop secured to said support and engag-
ing said block, a presser blade, means for
pivotally securing one end of the said blade
to said block, and further means for exert-
ing a yielding and adjustable pressure upon
the free end of said blade.
- 30 8. In a machine for finishing cigarette
seams, the combination with a frame, a
presser blade pivoted at one end to said
frame, a guide block movably engaging the
free end of the blade and secured to said

frame, a bore in said guide block, a spring
in said bore adapted to bear on said blade,
and a set screw in said block adapted to bear
on said spring.

50 9. In a machine for finishing cigarette
seams, the combination with a frame, a block,
a presser blade and means for pivotally se-
curing the presser blade comprising a
threaded bore in the block, an aperture in
the blade, and a screw having a threaded
stem for engagement with the threaded bore
in the block, a flange for engaging the side
of the presser blade, and a shoulder extend-
ing into the aperture of said blade and form-
ing a bearing therefor.

55 10. In a machine for finishing cigarette
seams, the combination with a frame, of
guide heads secured to said frame, a presser
blade engaging both guide heads and adapt-
ed to move vertically therein, and means in
one of the guide heads for exerting a yield-
ing and regulatable pressure upon the blade.

60 11. In a machine for finishing cigarette
seams the combination with a frame having
a plurality of guide heads, a presser blade
movably engaging said heads, means for pre-
venting a longitudinal displacement of the
blade with relation to said heads, means on
said heads for regulating the vertical move-
ment of the blade and for exerting a yielding
and regulatable pressure thereon.

65 12. In a machine for finishing cigarette
seams, the combination with a frame having
a plurality of guide heads, a presser blade
movably engaging the heads, a projection
on said blade, a stop passing through the
projection, and means secured to the heads
for exerting a yielding and regulatable pres-
sure upon the blade.

70 Signed at the city, county and State of
New York, this 14 day of March, 1913.

PAUL A. DRUCKLIEB.
